(57) **CLAIM**

I claim the ornamental design for multi-purpose tool for blade fuses, as shown and described.

DESCRIPTION

FIG. 1 is a right front perspective view of multi-purpose tool for blade fuses;

FIG. 2 is a front elevation view thereof;

FIG. 3 is a top plan view thereof;

FIG. 4 is a left elevation view thereof; and,

FIG. 5 is a right elevation view thereof.

The broken lines depict portions of the multi-purpose tool for blade fuses in which the design is embodied that are not considered part of the claimed design.
